(57) **CLAIM**

The ornamental design for a windowed closeable carton, as shown and described.

DESCRIPTION

FIG. 1 is a perspective view of a windowed closeable carton showing a new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a cross-sectional view taken in the direction of line 8-8 of FIG. 6;

FIG. 9 is a cross-sectional view taken in the direction of line 9-9 of FIG. 6;

FIG. 10 is another perspective view thereof, showing the windowed closeable carton in an open configuration;

FIG. 11 is another top plan view thereof, showing the windowed closeable carton in an open blank configuration.

FIG. 12 is a perspective view of another embodiment of a windowed closeable carton showing my new design, the right side elevation, left side elevation, bottom plan, and cross-section views being identical to those shown in FIGS. 2, 3, 7, 8 and 9 respectively;

FIG. 13 is a front elevation view thereof;

FIG. 14 is a rear elevation view thereof;

FIG. 15 is a top plan view thereof;

FIG. 16 is a cross-section view taken on line 16-16 of FIG. 15;

FIG. 17 is another perspective view thereof, showing the windowed closeable carton of FIG. 12 in an open configuration; and,

FIG. 18 is another top plan view thereof, showing the windowed closeable carton of FIG. 12 in an open blank configuration.
